UNITED STATES PATENT OFFICE.

PAUL KEMPE, OF MILWAUKEE, WISCONSIN.

BOTTLE-WASHER.

1,076,339.

Specification of Letters Patent.

Patented Oct. 28, 1913.

Application filed April 14, 1913. Serial No. 761,035.

To all whom it may concern:

Be it known that I, PAUL KEMPE, a citizen of the United States, residing at Milwaukee, in the county of Milwaukee, State of Wisconsin, have invented certain new and useful Improvements in Bottle-Washers, of which the following is a specification.

This invention relates to bottle washing devices operated by water power and the object thereof is to provide a simple, economical and efficient device of that character.

Further objects of this invention are to utilize the waste or exhaust water from the motor in the bottle washing process and to avoid retardation of the motor in so doing.

With the foregoing and other objects in view, the invention consists of the construction, combination and arrangement of parts hereinafter referred to and illustrated in the accompanying drawings which form a part of this specification.

In the drawings, wherein like reference characters denote corresponding parts throughout, Figure 1, is a side elevation of the device showing an axial section of the water motor. Fig. 2 is a rear elevation with the casing face *j* Fig. 1 removed.

Referring to the drawings, a water wheel *a* constructed with peripheral buckets *b* is fixedly mounted upon an axle *c* and inclosed in a suitable casing *d*, having bearings *e*, *e*, for said axle *c*, an opening *f* on one side for a water supply nozzle *g* and an opening *h* at the bottom for the escape of the waste water. Driving pulleys *i*, *i*, are mounted on either end of said axle *c* without the casing. One face *j* of the casing is removable. Upon the other face *k* of the casing and below the driving pulley *i* is attached a horizontal

arm *l*, the outer end of which is constructed with a U shaped prong, the members *m*, *m*, of which are provided with bearings for a vertical spindle *n*, upon which is mounted a driving pulley *o*, located between the afore-

mentioned prong members *m*, *m*, and provided with shoulders *p*, *p* which bear against the inner sides of said prong members and prevent any up or down motion to said spindle. The bottom end of said spindle *n*

is provided with suitable means, as by an axial hole and binding screw as shown at *q*, for holding a rotary bottle-washing brush *r*, which may be of any desired character, or size. Two free pulleys *s*, *s*, are mounted

horizontally on either side of the horizontal arm *l* and below the driving pulley *i* in such

manner as to guide a driving belt *t*, passing around the driving pulleys *i* and *o*.

It will be apparent that the brush carrying spindle here shown and described as vertical may be located in other relative positions, either oblique or horizontal, and modifications in the mode of driving said spindle will readily suggest themselves to those skilled in the art.

In the bottom opening *h* of the casing, provided for the escape of the waste water from the water wheel, is provided a water-catching cup *u*, smaller in size than said opening *h* and provided with a water stopping lip *v* so arranged as to intercept and deflect into said cup *u* the waste water from the buckets *b*. A drain pipe *w* is provided to carry the water from the cup *u* and apply the same to the bottle washing brush *r*.

In operation the water applied through the nozzle *g* will drive the wheel *a* by its downward tangential impact, thus operating the rotary bottle-washing brush *r* by means of the driving pulleys *i* and *o* and belt *t*, guided by the free pulleys *s*, *s*. Other work may be done simultaneously by a belt applied to the other driving pulley *i*, or same may be omitted, as desired. The water having driven the wheel, will be intercepted and deflected by the lip *v* of the water catching cup *u*, and from said cup so much will be drawn off through the drain pipe *w* as is needed at the bottle washing brush *r*. Any surplus water will overflow from said cup *u*, which being smaller than the opening *h* in the bottom of the casing, allows for the ready escape of such overflow from the casing, without clogging or retarding the water wheel.

Having thus fully described my invention, I claim:

1. In a bottle washer, a water wheel, a casing for said wheel having an opening in the bottom for the exhaust of water, a spindle supported outside and upon said casing, a bottle-washing brush carried by said spindle, means for applying water to the water wheel, means for driving said spindle and brush from the water wheel, means within the bottom opening of said casing for intercepting and receiving a part of the exhaust water, and means for conveying such intercepted portion of exhaust water to the bottle-washing brush.
2. In a bottle washer, a water wheel, a casing for said wheel having an opening in

the bottom for the exhaust of water, a spindle supported outside and upon said casing, a bottle-washing brush carried by said spindle, means for applying water to the water wheel, means for driving said spindle and brush from the water wheel, a water intercepting cup supported by said casing within said bottom opening, said cup being smaller in size than said opening and so located therein as to leave a free space for the ready discharge of any overflow water therefrom, and means for conveying water from said cup to the bottle-washing brush.

3. In a bottle washer, a water wheel, a casing for said wheel having an opening in the bottom for the exhaust of water, a vertical spindle supported outside and upon said

casing, a bottle-washing brush carried by said spindle, means for applying water to said water wheel, means for driving said spindle and brush from the water wheel, a water intercepting cup supported by said casing within said bottom opening, and provided with a water deflecting lip, said cup being smaller in size than said opening and so located therein as to leave a free space for the ready discharge of any overflow water therefrom, and means for conveying water from said cup to the bottle-washing brush, substantially as shown and described.

PAUL KEMPE.
